UNITED STATES PATENT OFFICE.

ISHMAEL BAIR, OF SOUTH BEND, INDIANA.

SPRING BED-BOTTOM.

SPECIFICATION forming part of Letters Patent No. 289,493, dated December 4, 1883.

Application filed August 17, 1883. (No model.)

To all whom it may concern:

Be it known that I, ISHMAEL BAIR, a citizen of the United States, residing at South Bend, in the county of St. Joseph and State of Indiana, have invented certain new and useful Improvements in Bed-Slats, of which the following is a specification, reference being had therein to the accompanying drawings.

My invention relates to certain new and useful improvements in elastic bed-bottoms; and it consists in arranging the slats of a bedstead at equal distance apart to form a bed-bottom, and support them in said position on elastic material.

15 The object of my invention is, first, to form a cheap and durable elastic bed-bottom, adapted for use on all ordinary bedsteads; second, to construct the essential features of my invention in such a manner that they may 20 be applied to the common slat-bottom bedstead, to change the same into a spring-bottom bedstead at a trifling expense. I attain these objects by means of the peculiar construction and arrangement of the various 25 parts of my invention, which will be more fully pointed out and described in the specification and claims, referring to the drawings accompanying this application and forming a part of the same, in which—

30 Figure 1 is a bottom plan view of my invention, showing the different parts in place. Fig. 2 is a vertical sectional view of the same, and Fig. 3 is a cross-section of the longitudinal slats and rings.

35 Similar letters refer to similar parts throughout the drawings.

Reference being had to the drawings, A represents an ordinary bedstead, having foot-boards, side rails, and head-boards. A projection, d, is formed on the inner face of side rails, B, in the usual form, to receive the ends of cross-slats a, as shown in Fig. 2, said cross-slats being arranged to extend from the inner face of one side rail to the inner face of the opposite rail, and are usually placed one at the foot and one at the head of the bedstead, as shown in Fig. 2; but in case the ordinary cross-slats are used (instead of extra slats prepared for the purpose) to form the

longitudinal strips d', then an extra cross-slat 50 is placed across the center of the bed in the usual form, as shown in Fig. 1. Said cross-slats a are formed about two inches wide, and of sufficient length to reach across the bedstead and on the under side of the same. Elastic web 55 b (preferably rubber) is secured by screw-bolts or rivets, each end of said web b being secured to each end of slats a, the remaining portion being loose, but lying close to the slat a. Rings c are formed of metal, rounding on their outer surface and angular on their inner surfaces to fit around the cross-slat a and web b, as shown in cross-section in Fig. 2. Said rings, when placed in position on slats a, serve to keep the slats d' in place and hold the 60 elastic web against the same, while the web b is allowed to yield when weight is placed on said slats.

In forming a bed-bottom with my invention, cross-slats a are prepared in the usual form, 70 when elastic web is secured by its ends to the ends of the slats a by means of nails or screw-bolts e, said web b being about the same width as the slats a, and of the same length, said web being drawn smoothly along the under face of slats a. Slats a are then placed in position in a recess formed in projection d, one at the foot and one at the head of the bed, and when desired, one at the center of the bed. A longitudinal slat, b, is then inserted 80 between the elastic web b and the slats a, said slat resting by its ends on the web b. A ring, e, is slipped over the web and slats a, close to the side of slat d', which is forced close to the end of slats a. Another slat, d', is inserted in 85 like manner, followed by the rings c, and thus the operation is repeated until the bed-bottom is completed. This construction forms a cheap and durable elastic bed-bottom, that can be easily applied to almost any bedstead 90 in use.

I am aware of the Patent No. 52,658, February 20, 1866, its construction, and the arrangement of the various parts of the same, and I therefore do not broadly claim the same; 95 but

What I do claim is as follows:

In a bed-bottom, the cross-slats a, con-

structed as described, whereby they will fit in and rest on the interior supporting flange of a slat bedstead, having each a rubber web or strip, *b*, secured to its lower side and at the 5 extremities, as shown, in combination with longitudinal slats *d*', and the rings *e*, all constructed and arranged substantially as shown and specified.

In testimony whereof I affix my signature in presence of two witnesses.

ISHMAEL BAIR.
